[57] CLAIM

The ornamental design for an insulated container, substantially as shown and described.

DESCRIPTION

FIG. 1 is a top, front, left side perspective view of an insulated container showing my new design, the strap shown in broken lines for illustrative purposes only;

FIG. 2 is a right side elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view thereof shown in an open position;

FIG. 8 is a top plan view thereof shown in an open position;

FIG. 9 is a perspective view of a second embodiment shown in an open position; and

FIG. 10 is a top plan view of FIG. 9 shown in an open position.
